UNITED STATES PATENT OFFICE.

ALFRED A. HOLLOWAY, OF DALLAS, TEXAS.

BLOW-OUT GUARD.

1,115,540.

Specification of Letters Patent.

Patented Nov. 3, 1914.

Application filed March 16, 1914. Serial No. 824,849.

To all whom it may concern:

Be it known that I, ALFRED A. HOLLOWAY, citizen of the United States, residing at Dallas, in the county of Dallas and State of Texas, have invented certain new and useful Improvements in Blow-Out Guards, of which the following is a specification.

My invention relates to a new and useful blow-out guard for double tube tires, and its object is to provide a split sleeve of suitable material which may be interposed between the inner and outer tubes of a pneumatic tire, to reinforce an apertured or weakened place in the outer tube or casing, preventing the inner tube from "blowing out" at such a point.

It is a further object of the invention to provide a blow out guard that may be very quickly applied to the tire without the use of special tools or mechanical skill, and which will securely remain in its proper place in the tire until manually removed.

Finally the object of the invention is to provide a device of the character described, that will be strong, durable, simple and efficient and comparatively easy to construct.

With these and various other objects in view, my invention has relation to certain novel features of the construction and use, an example of which is described in the following specification, and is illustrated in the accompanying drawing, wherein:

Figure 1 is a view showing in side elevation the application of my blow out guard to a double tubed tire, the outer tube or casing being partially broken away to more clearly illustrate the blow out guard. Fig. 2 is a view showing in side elevation the blow out guard alone. Fig. 3 is a transverse sectional view, taken upon the line x-x of Fig. 1.

Referring now more particularly to the drawing, wherein like reference characters designate similar parts in all the figures, the numerals 1 and 2 respectively denote the outer and inner casings of an ordinary double tube tire, and 3 denotes a split sleeve, the longitudinal edges of which are slightly spaced when said sleeve is made to embrace the casing 2. The material composing the sleeve 3 will preferably be a combination of canvas and rubber such as will give great strength without permitting the passage of air. Within the sleeve, there is secured to one of the longitudinal edges thereof a tongue 4, which when the sleeve is inter-

posed between the inner and outer casings of a tire extends across the gap between the adjacent longitudinal edges of the sleeve 3, counteracting the tendency of the inner casing to bulge through said gap due to air pressure. It is preferred to thicken the central portion of the tongue 4 as indicated at 4^a, since said central portion is exposed to the greatest pressure by the inflated inner tube. The tongue 4 may be formed of similar material to that composing the sleeve 3.

Adjacent to one of the longitudinal edges of the sleeve 3 there is exteriorly secured a strip 5 of flexible material, preferably leather, a row of stitching 5^a being preferably employed to secure said strip to the sleeve 3. The strip 5 projects slightly beyond the adjacent edge of the sleeve 3, and is formed with a plurality of equidistant loops 6. To the other longitudinal edge of the sleeve there is exteriorly secured a strip 7 of flexible material, preferably leather, and secured to the sleeve 3 preferably by a row 7^a of stitching 7^a. In the strip 7 there are provided a plurality of slots 8, through which the loops 6 may be respectively passed as is clearly shown in Fig. 1 of the drawing.

To one extremity of the strip 7 there is riveted or otherwise secured a thong 9, which after the loops 6 have been projected through the slots 8 will be passed through all of said loops, thus positively preventing the withdrawal of the loops from the slots, and holding the inner casing firmly embraced within the sleeve 3 when said casing is inflated.

By the use of the above described device a weakened outer casing may be so reinforced that its period of usefulness will be very much increased. The device can further be used to great advantage to temporarily repair a tire subsequent to a blow out, the inner tube being patched in this case at the point where it has given away, and my blow out guard being employed to protect the patch until the outer casing can be vulcanized at the weakened point.

The invention is presented as including all such modifications and changes as properly come within the scope of the device as claimed.

What I claim is:

1. In a blow out guard for pneumatic tires, a flexible air proof sleeve split longitudinally, a flexible member folded upon it-

self and cut out along the fold whereby a plurality of spaced marginal loops are provided integrally with said folded member, said folded member being secured to the exterior face of one of the longitudinal edges of said sleeve, a flexible strip secured to the opposite longitudinal edge of the sleeve, and provided with elongated slots having their longitudinal axes parallel to the longitudinal axes parallel to the longitudinal edges of the sleeve, each slot receiving one of the loops of the folded member, a flat thong secured at one of its ends to one end of the last named strip and laced through the loops of the folded member, and a third strip of flexible material secured to the inner face of one of the longitudinal edges of the sleeve and bridging the gap between the longitudinal edges of the sleeve, the thickness of said third strip being increased between the longitudinal edges of the sleeve.

2. In a blow out guard for pneumatic tires, a flexible air proof sleeve split longitudinally, a flexible member folded upon itself and cut out along the fold whereby a plurality of spaced flat marginal loops are provided integrally with said folded member, said folded member being secured to the exterior face of one of the longitudinal edges of said sleeve, a flexible strip secured

to the opposite longitudinal edge of the sleeve, and provided with elongated slots 25 having their longitudinal axes parallel to the longitudinal edge of the sleeve, each slot receiving one of the loops of the folded member, a flat thong secured at one of its ends to one end of the last named strip and 30 laced through the loops of the folded member, and a third strip of flexible material secured to the inner face of one of the longitudinal edges of the sleeve and bridging the gap between the longitudinal edges of the 35 sleeve, the thickness of said third strip being increased between the longitudinal edges of the sleeve.

In testimony whereof I have signed my name to this specification in the presence of 40 two subscribing witnesses.

ALFRED A. HOLLOWAY.
